UNITED STATES PATENT OFFICE.

WILLIAM S. A. WILDER, OF ANDERSON, CALIFORNIA.

DEVICE FOR REMOVING AND REPLACING RAILROAD-TIES.

1,078,182.

Specification of Letters Patent. Patented Nov. 11, 1913.

Application filed April 9, 1913. Serial No. 759,845.

To all whom it may concern:

Be it known that I, WILLIAM S. A. WILDER, a citizen of the United States, residing at Anderson, in the county of Shasta and State of California, have invented new and useful Improvements in Devices for Removing and Replacing Railroad-Ties, of which the following is a specification.

This invention relates to a railroad-tie removing and replacing device.

The object of this invention is to provide a simple and easily operated device by which the old ties of a railroad track may be easily removed and replaced by new ties, without disturbing or removing the surrounding road-bed.

The invention consists of the parts and the construction and combination of parts as hereinafter more fully described and claimed, having reference to the accompanying drawings, in which—

Figure 1 is a central section of the device, showing its position upon the rails. Fig. 2 is a cross section on the line X—X of Fig. 1. Fig. 3 is a detail view of the ratchet mechanism. Fig. 4 is a perspective view of the plow member. Fig. 5 is an end view of a track, showing the application of the invention.

Referring to the drawings: A indicates in particular the road-bed upon which is placed the usual form of ties 2 and rails 3. The object of this invention, as before stated, is to provide means by which the old partly-rotted ties may be removed and replaced by new ones without disturbing or removing the surrounding road-bed. This is accomplished by a specially constructed form of ratchet jack which consists of a pair of side plates 4 suitably secured together by bolts 5. Slidably mounted between the plates 4, upon rollers 7 appropriately journaled between the plates 4, is a longitudinal bar 8, upon the sides of which are formed rack-teeth 9 and 10, adapted to be actuated by a pair of pawls 11 and 12, pivotally mounted as at 13 and 14 in a lever 15, pivotally mounted as at 16 between the side plates 4 and adapted to be rocked by the application of handles 17, which are secured in pocket members 18 formed on the lever 15. The lever may be rocked through the handle 17 by manual labor, and will when rocked about the pivot 16 transmit reciprocal movement to the pawls 11 and 12, which movement in turn will be trans-

mitted through the ratchet teeth 9 and 10 to force the longitudinal bar 8 in the direction of arrow a. One end of the bar 8 is provided with an upwardly turned hook member 19, which becomes engageable with a spring-actuated catch pawl 20, pivotally mounted as at 21 between the plates. The hook 19 and the catch pawl 20 are provided for the purpose of limiting the outward movement of the bar 8; or in other words, to prevent its complete removal from the plates. The opposite end of the bar 8 is provided with a downwardly projecting jaw 22, which extends downwardly a sufficient distance to engage with the end of the tie 2, upon which the rails 3 are mounted.

In order to secure the ratchet jack here shown upon the rails when it is placed in position with relation to a tie, it is accomplished by forming suitable depressions 6 in the lower edges of the plates, which are adapted to straddle the tracks, as shown in Figs. 1 and 5.

In operation when it is desired to remove the tie 2, indicated in Fig. 1, it is accomplished by placing the ratchet jack upon the tracks in such position as to cause the depressions 6 to grip the rails 3. The lever 15 is then rocked by the handle 17 until the downwardly projecting jaw 22 engages with the end of the tie 2. A continued rocking movement of the lever 15 will thus cause the bar 8 and jaw 22 to move in the direction of arrow a and force the tie outward in the direction of the arrow to the dotted line position indicated at 23. The position of the rail limits any further movement of the bar and jaw 22, as at this point engagement is made with the supporting rail. It then becomes necessary to return the ratchet bar 8 to its extreme outward position, indicated in Fig. 5. In order to return the ratchet bar 8 to this position, it becomes necessary to elevate the pawls 11 and 12 out of engagement with the ratchet teeth 9 and 10 formed on the sides of the bar 8. This is accomplished by providing the pivot member 13 of the pawl 11 with a lever 24, which is turned upward in the direction of arrow b, shown in Fig. 3, in which position the end of the lever 24 is retained by a latch or hook 25. The movement of the lever from its normal position, indicated in Fig. 3, to the elevated position assumed when brought into engagement with the latch 25, is transmitted through the

pivot member 13 and pawl 11 to lift this, together with the pawl 12, into position where they are out of engagement with the ratchet teeth 9 and 10 formed on the bar. 5 The bar 8 having thus been released from engagement with the pawls 11 and 12 and moved to its extreme outer position, indicated in Fig. 5, is then returned by rocking the lever 15 through the medium of the handle 10 17. A new tie, as indicated at 26, having been interposed between the old tie 2 and the jaw 22, the movement of the bar 8 and jaw 22 will thus be transmitted through the new tie 26 to force the old tie 2 out from 15 under the track and force the new tie 26 into the position formerly occupied by the old tie.

In some instances it often happens that the old tie becomes so deteriorated that the space occupied by same is considerably less than that occupied by a new tie. It thus becomes necessary to remove a film of earth of sufficient thickness to make place for the new tie, which is to be inserted beneath the rails 3. This is accomplished by interposing a plow member 27, indicated in Fig. 4, between the old tie and the new tie. The plow member is provided with serrations or teeth 28 which engage the surrounding material which is forced upward through the curved channels 29 formed on each side of the plow as the tie is advanced into position. The forward portion of the plow is provided with a contact plate 30, which engages with the rear portion of the old tie to force this out of position, while the rear of the plow is provided with a shoe 31 and a sharp projection 32 which becomes thoroughly embedded in the forward portion of the new tie. This means being provided for the purpose of securing the plow in perfect alinement and preventing its accidental removal from the forward portion of the tie 26, or from engagement with the old tie 2 which is being forced out of position by the pressure of the bar 8, which is transmitted through the jaw 22 and tie 26. The forward face of the plow is of exactly the same area as the cross area of the tie, and will thus 50 cause the accumulation of road-bed material to be forced out of the path, this being projected upward through the curved pockets 29 formed on the forward portion of the plow.

55 The device here shown is simple and compact in construction and may be easily operated by unskilled labor. By providing the plow attachment shown, it is possible to remove the necessary quantity of material 60 during the operation of replacing the tie.

The materials and finish of the several parts of the ratchet jack are such as experience and judgment of the manufacturer may dictate.

65 Having thus described my invention,

what I claim and desire to secure by Letters Patent is:

1. The combination in a railroad tie removing and replacing device of a pair of interspaced plate members secured with relation to each other, a bar slidably mounted between the plates, a downwardly projecting jaw formed on the end of the bar adapted to engage with the end of a tie, means for securing the plate members on the rails of the track, means for moving the bar between the plates, and means for clearing the path in front of the new tie. 70

2. The combination in a railroad tie removing and replacing device of a pair of interspaced plate members secured with relation to each other, guide rollers journaled in said plates, a ratchet bar mounted between said rollers, a downwardly projecting jaw formed on the end of the bar adapted to engage with the end of a tie, means for moving the ratchet bar between the rollers, means for preventing the complete removal of the ratchet bar from the plates and rollers, and means for securing the plate members on the rails of the track. 80

3. The combination in a railroad tie removing and replacing device of a pair of interspaced plate members secured with relation to each other, guide rollers journaled in said plates, a ratchet bar mounted between said rollers, a downwardly projecting jaw formed on the end of the bar adapted to engage with the end of a tie, a lever pivotally mounted between the plates, a pair of pawl members pivotally mounted in said lever adapted to engage with the ratchet bar, means for rocking the lever and connected pawls to move the ratchet bar, means for preventing the complete removal of the ratchet bar from the plates and rollers, means for lifting and retaining the pawls out of engagement with the ratchet bar, and means for securing the plate members on the rails of the track. 95

4. The combination in a railroad tie removing and replacing device of a pair of interspaced plate members secured with relation to each other, guide rollers journaled in said plates, a ratchet bar mounted between said rollers, a downwardly projecting jaw formed on the end of the bar adapted to engage with the end of a tie, a lever pivotally mounted between the plates, a pair of pawl members pivotally mounted in said lever adapted to engage with the ratchet bar, means for rocking the lever and connected pawls to move the ratchet bar, a hook formed on the opposite end of the ratchet bar, a spring-actuated pawl pivotally mounted between the plates adapted to engage with the hook member to prevent the complete removal of the ratchet bar from between the plates and rollers, a lever connected with one of the ratchet bar actuating 110

pawls adapted to lift the pawls out of engagement with the ratchet bar, a catch for holding the lever in the released position, and depressions formed in the lower edges 5 of the plate members adapted to straddle the rails and secure the plates in position when it is desired to remove and replace a tie.

5. The combination in a railroad tie removing and replacing device of a pair of interspaced plate members secured with relation to each other, guide rollers journaled in said plates, a ratchet bar mounted between said rollers, a downwardly projecting 10 jaw formed on the end of the bar adapted to engage with the end of a tie, a lever pivotally mounted between the plates, a pair of pawl members pivotally mounted in said lever adapted to engage with the 15 ratchet bar, means for rocking the lever and connected pawls to move the ratchet bar, a hook formed on the opposite end of the ratchet bar, a spring-actuated pawl pivotally mounted between the plates adapted to 20 engage with the hook member to prevent the complete removal of the ratchet bar from between the plates and rollers, a lever connected with one of the ratchet bar actuating 25 pawls adapted to lift the pawls out of en-

gagement with the ratchet bar, a catch for holding the lever in the released position, 30 depressions formed in the lower edges of the plate members adapted to straddle the rails and secure the plates in position when it is desired to remove and replace a tie, 35 and a plow member adapted to be secured on the end of the new tie that is being replaced to clear the path for said tie.

6. The combination in a railroad tie removing and replacing device of a ratchet 40 bar, a frame in which said bar is slidably mounted, means for securing the frame to the track, a downwardly extending jaw formed on the outer end of the ratchet bar adapted to hold one end of a new tie, 45 a plow member adapted to be secured between the other end of the tie and the old tie to remove any material which might obstruct the path of the new tie, and means for moving the ratchet bar to remove the 50 old tie and replace a new tie.

In testimony whereof I have hereunto set my hand in the presence of two subscribing witnesses.

WILLIAM S. A. WILDER.
